J. A. SEEDE

ELECTRIC FURNACE

Filed June 5, 1926

Inventor:
John A. Seede,
by *Wm. S. Lunt*
His Attorney

UNITED STATES PATENT OFFICE.

JOHN A. SEEDE, OF SCHENECTADY, NEW YORK, ASSIGNOR TO GENERAL ELECTRIC COMPANY, A CORPORATION OF NEW YORK.

ELECTRIC FURNACE.

Application filed June 5, 1926. Serial No. 114,010.

My invention relates to electric furnaces, more particularly to electric smelting furnaces of the electrode type, such as used in the production of ferro-alloys, calcium carbide, etc., and has for its object the provision of simple and reliable control means whereby the electric heating current may be caused to pass either from one electrode to another or from one or more electrodes 10 through the charge and the furnace lining.

In carrying out my invention in one form as applied to a three-phase circuit, I provide three electrodes in the top of the furnace which are connected to the secondary terminals of a three-phase supply transformer and a fourth electrode embedded or otherwise connected in the bottom of the furnace crucible and electrically connected to the neutral point of the transformer secondary. I also provide means for reversing the connections of one coil of the transformer primary winding so as to control current through the bottom electrode.

For a more complete understanding of my invention, reference should be had to the accompanying drawing, the single figure of which shows in somewhat diagrammatic fashion, an electric furnace embodying my invention.

Referring to the drawing, I have shown my invention in one form as applied to a smelting furnace, the furnace structure comprising a crucible 10 made of a suitable heat refractory material, such as "fire clay". This crucible as shown, is mounted in a jacket of heat refractory bricks 11. A pouring orifice 12 communicates with the bottom of the reservoir 13 for the charge 14. As shown, this orifice is plugged by means of a clay ball 12^a.

The charge is heated by means of three vertically arranged carbon electrodes 15, 16 and 17 which are suitably supported in a well-known manner so as to hang downward into the reservoir 13 into electrically conducting or arcing relation with the charge. These three electrodes are connected through a transformer 18 with a suitable three-phase alternating current supply source 19, the electrodes being connected directly to the terminals of the transformer secondary winding 20, which consists of three coils, 20^a, 20^b, and 20^c connected in star. A connection is also provided from 55 a neutral point 21 of the secondary wind-

ing through a conductor 22 to the bottom of the crucible 10. As shown, this connection is made by means of a bottom electrode 23 which is embedded in the bottom wall of the crucible 10 and connected with the conductor 22.

The primary winding 24 of the transformer has its coils connected in delta to the supply source 19. The connections for one of the primary windings, however, are such that they can be reversed. As shown, the primary winding 25 is connected to the supply source through a reversing switch 26. With the switch thrown downward to the position shown in the drawing, the primary coils are connected in delta and the secondary coils have the usual 120° three phase voltage relationship. By throwing the switch upward to its other position the connections for the winding 25 are reversed whereby the voltage of the coil 20^c of the secondary winding is reversed so that this coil has a 60° voltage phase relation with respect to the voltages of the other two secondary coils 20^a and 20^b.

In the operation of the furnace the switch 26 will normally be thrown to its lower position as shown in the drawing and under these conditions of operation no current will flow through the conductor 22 and the bottom electrode 23 as long as the load between the three electrodes 15, 16 and 17 is balanced.

With the heat for the furnace generated in this manner by the current passing between the three upper electrodes 15, 16 and 17, it will be observed that the heat is generated at the top of the charge and consequently the temperature will be much higher at the top than at the bottom. Ordinarily, 95 arcs will be formed between the upper electrodes and the charge, and the lengths of the arcs will be varied as desired by adjusting the electrodes vertically so as to regulate the rate of heat generation.

Under certain conditions it may be desired to raise the temperature of the bottom of the charge. This may be necessary, for example, in case the molten product has solidified around the outlet orifice 12 so as to close it. In such case the switch 26 is thrown to its upper position a suitable time prior to the pouring of the product whereby a current is caused to pass between the bottom electrode and the three upper elec- 110

2
trodes, the crucible 10 electrically conduct-
ing at the temperature involved. This cur-
rent is substantially twice the current nor-
mally flowing in each of the upper elec-
trodes and the bottom of the crucible will
be rapidly heated by reason of its own re-
sistance and also the resistance of the charge
to some extent. In this way any product
clogging the pouring orifice will be melted
out.

While I have described my invention as
embodied in concrete form and as operating
in a specific manner in accordance with the
provisions of the Patent Statutes, it should
be understood that I do not limit my inven-
tion thereto since various modifications
thereof will suggest themselves to those
skilled in the art without departing from
the spirit of my invention, the scope of
which is set forth in the annexed claims.

What I claim as new and desire to secure
by Letters Patent of the United States, is—

1. The combination with a metal melting
furnace provided with a plurality of elec-
trodes above the charge, a three phase source
of electrical supply, transformer means com-
prising primary and secondary coils, said
secondary coils being star connected, con-

nections between the terminals of said sec-
ondary coils and said upper electrodes, a 30
connection between the neutral point of said
secondary coils and the bottom of said fur-
nace, electrical connections between said pri-
mary coils and said supply source, and
means for reversing the connections of one 35
of said primary coils so as to reverse the
polarity of one of said secondary coils.

2. The combination with a metal melting
furnace provided with three upper elec-
trodes and a bottom electrode, a three phase 40
source of supply, a three phase transformer
having delta connected primary coils and
star connected secondary coils, connections
between the terminals of said secondary
coils and said upper electrodes, a connection 45
between the neutral point of said secondary
coils and said bottom electrode, electrical
connections between the primary coils of
said transformer and said supply source, and
means for reversing the connections of one 50
of said primary coils whereby a current is
caused to flow through said bottom electrode.

In witness whereof, I have hereunto set
my hand this 4th day of June, 1926.

JOHN A. SEEDE.
